Primary Examiner — Karen E Eldridge Powers(74) *Attorney, Agent, or Firm* — David M. Fortunato; Cohen Pontani Lieberman and Pavane LLP(57) **CLAIM**

The ornamental design for an injection device with sealed luer fitting, as shown and described.

DESCRIPTION

FIG. 1 is an exploded, perspective view of a injection device with sealed luer fitting, with the housing shown in dashed lines illustrating environmental matter and forming no part of the claim;

FIG. 2 is a perspective view thereof;

FIG. 3 is a top view thereof;

FIG. 4 is a front view thereof;

FIG. 5 is a right side view thereof;

FIG. 6 is a left side view thereof;

FIG. 7 is a rear view thereof;

FIG. 8 is a bottom view thereof; and,

FIG. 9 is a cross-sectional view taken from line 9-9 of FIG. 2, with the interior edges shown in dashed lines illustrating environmental matter and forming no part of the claim.
